UNITED STATES PATENT OFFICE

144,093

DESIGN FOR A PASTRY SHELL FRAME OR INSERT

Ellen H. Abell, Metuchen, N. J.

Application October 11, 1945, Serial No. 122,737

Term of patent 14 years

(Cl. D44—29)

To all whom it may concern:

Be it known that I, Ellen H. Abell, a citizen of the United States, residing at Metuchen, in the county of Middlesex and State of New Jersey, have invented a new, original, and ornamental Design for a Pastry Shell Frame or Insert, of which the following is a specification, reference being had to the accompanying drawing, forming part thereof.

I claim:

The ornamental design for a pastry shell frame or insert, as shown.

ELLEN H. ABELL.
